UNITED STATES PATENT OFFICE.

JOHN F. THOMPSON, OF NEW YORK, N. Y., ASSIGNOR TO G. A. PRATT & CO.,
OF SAME PLACE.

DESIGN FOR A RADIATOR.

SPECIFICATION forming part of Design No. 32,710, dated May 22, 1900.

Application filed April 23, 1900. Serial No. 14,050. Term of patent 14 years.

To all whom it may concern:

Be it known that I, JOHN F. THOMPSON, a citizen of the United States, and a resident of the city of New York, borough of Manhattan, in the county and State of New York, have invented and produced a new and original Design for a Radiator, of which the following is a full, clear, and exact description.

Reference is to be had to the accompanying drawings, forming a part of this specification, in which similar characters of reference indicate corresponding parts in all the figures.

Figure 1 is an end view of a heat-radiator, showing my design. Fig. 2 is a front view, and Fig. 3 is a top or plan view.

A leading feature of my design for a heat-radiator consists in a series of radiating-tubes, comprising front members 1 and rear members 2, which have their outer surfaces convergent. The radiator-tubes extend upward from a base 3, the walls of which are inclined

downward and outward, and this base is supported on legs 4.

Another feature of the design consists in the wave-like upper wall 5 of the base, in which perforations 6 appear, and, further, in the plate-like structure 7, which extends partly over the top of the radiator-tubes, and in which perforations 8 appear.

Having thus described my invention, I claim as new and desire to secure by Letters Patent—

The design for a radiator, as herein shown and described.

In testimony whereof I have signed my name to this specification in the presence of two subscribing witnesses.

JOHN F. THOMPSON.
